CLAIM

I claim the ornamental design for a thimble for needle work, as shown and described.

DESCRIPTION

FIG. 1 is a perspective view of a thimble for needle work;

FIG. 2 is a front view of the thimble;

FIG. 3 is a rear view of the thimble;

FIG. 4 is a top plan view of the thimble;

FIG. 5 is a bottom view of the thimble;

FIG. 6 is a left side view of the thimble, the right side view being symmetric to the left side view; and,

FIG. 7 is a perspective view illustrating how the thimble is used.

The broken lines in FIG. 7 are included for the purpose of illustrating the environment and form no part of the claimed design.
